UNITED STATES PATENT OFFICE.

ARTHUR T. GOODING, OF LONDON, ENGLAND.

COMBINED BABY'S HIGH CHAIR AND COT.

Application filed October 11, 1923. Serial No. 667,968.

The present invention consists of a combined baby's high chair and cot the principal object of which is to provide a high chair which may be used in the usual way, without 5 possibility of the occupant throwing itself therefrom, and being so constructed that it may be quickly and conveniently converted into a cot to permit the occupant to lie down.

A further object of this invention is to provide an article of furniture which is comparatively simple in construction, inexpensive to manufacture and durable and will prove a great convenience with children.

Other objects of the invention will be apparent from the following description of the invention taken in connection with the accompanying drawings wherein:

Fig. 1 is a front elevational view of a chair constructed in accordance with this invention;

Fig. 2 is a side elevational view thereof showing the tray slightly elevated;

Fig. 3 is a fragmentary rear elevational view of the chair back parts of which are open 25 to disclose details;

Fig. 4 is a side elevational view of the chair showing the same converted into a cot;

Fig. 5 is a fragmentary vertical sectional view of the chair showing to advantage the 30 construction of the chair back;

Fig. 6 is a fragmentary rear elevational view of the chair back illustrating the manner in which it is closed when used as a chair per se;

Figure 7 is a fragmentary plan of one side 35 of the back when lowered to a horizontal position; and

Figure 8 is a fragmentary vertical section on line 8—8 of Figure 2.

The present invention consists of a supporting structure or base 7 composed of a plurality of legs connected by cross bars, the legs diverging toward their lower ends to minimize the possibility of the chair being 40 tilted by the occupant. The upper ends of the legs are engaged by arms 8 to which a tray 9 is pivotally connected. A foot rest 10 is pivoted beneath the front legs of the chair.

In order to support the baby, a seat 11 is 45 provided which may be made of canvas or other suitable material and is provided with leg openings 12 in the front thereof through which the legs of the infant may be projected. The front of the seat 11, between the apertures 12, is formed to provide a flap 13 which may be opened to permit free movement of the

legs of the child when the chair is used as a cot in a manner hereinafter described. Upon reference to Fig. 5 of the drawings it will be noted that the seat consists merely of two 50 sides and a front, the back being omitted since the child is permitted to rest its back directly against the chair back which will be presently described. The upper marginal edges of the canvas or other material comprising the seat 55 is convoluted around and secured to rods 14 in an obvious manner.

Pivotaly mounted between the upper rungs of the chair, as indicated at 15, is a back generally designated 16. The back is 60 adapted to be disposed at an inclination to support the occupant of the seat 11 and is held in an inclined position by a thumb screw 17 which extends through one of the rear legs of the chair and into a complementary recess 75 formed in one of the sides of the chair back as illustrated in Fig. 2.

The chair may be quickly converted into a cot by removing the thumb screw 17 and permitting the upper end of the back 16 to 80 gravitate into a position where the lower end of the back lies directly beneath the seat 11. In this position an aperture 19 in the side of the back 16 is in alignment with an aperture 20 formed in one of the chair legs and these 85 apertures are adapted to be engaged by the thumb screw 17 thereby holding the chair back in a fixed position. The lower end of the chair back is equipped with a lip 21 which engages the foot rest 10 subsequent to urging 90 the latter upwardly into the position shown in Fig. 4 of the drawings. In this way, the foot rest is arranged to cooperate with the back rest and seat so as to support the feet 95 of the occupant when the device is used as a cot.

The outer end of the back 16 is supported by a hinged prop structure 22 which is normally mounted within the confines of the back 16. If desired, a shade for the eyes of the occupant, as designated at 23, may be 100 pivotally mounted within the prop structure 22. The shade can be moved on its axis into a position at right angles to the back 16 or any intermediate angle for the purpose of shading the eyes of the occupant. Moreover, 105 in order to prevent the occupant from rolling over the sides of the back 16, suitable adjustable retaining sides are provided as indicated at 24. These sides may be made of canvas or other suitable material and are secured to the sides 110 of the back 16. They may be bent upwardly around the sides of the back 16, as shown in

Figure 4 so as to form side walls for the cot. The free side edges of the sides 24 are reinforced by strips 24^a which engage over arms 24^b carried by the shade 23 for holding the upper or outer ends of the sides 24 in proper raised positions. The opposite ends of the sides 24 are held in elevated position by means of members 25 pivotally carried by the rear ends of the arms 8 of the chair, said members 25 engaging under lugs 25^a on the outer sides of the reinforcing strips 24^a. Stops 25^b are also carried by the arms 8 of the chair for engaging the inner sides of the sides 24 to aid in holding said sides in proper positions. A retaining flap 26 may be employed to further prevent the possibility of the occupant falling out or throwing itself out of the device when used as a cot, this flap being engageable beneath retaining strips 27 which are mounted upon the ends of the seat 11 and secured to the seat by means of suitable snap fasteners 27^a carried by the seat and by the flaps. Also, when the device is used as a cot the flap 13 between the apertures 12 of the seat is permitted to drop down as shown by the dotted lines in Fig. 1 to permit free movement of the legs of the occupant.

When the device is used as a chair the prop structure 22, shade 23 and retaining sides 24 are folded into the back 16. The flaps 24 are held together by suitable fasteners 28 which may be the usual stud and socket fasteners. Moreover, the flap 26 may be engaged with the sides 24 by stud and socket fasteners as illustrated in Fig. 6.

It is of course to be understood that the device of the present invention is capable of other uses and may be modified in this case to produce analogous results. It is to be understood that such changes, as well as other changes in the details of construction, proportion and arrangement of parts are embodied in the scope of the present invention as covered by the appended claim.

What is claimed is:—

A convertible chair comprising a base structure, a seat of flexible material secured at its ends to the upper opposite side portions of the base structure, a foot rest hingedly mounted at the forward portion of the base structure, a back pivoted to the base structure near the level of the lowermost portion of the seat, said back being detachably secured to the base structure at a point above and to the rear of the pivotal connection between the back and base structure, a lip secured to a portion of the back projecting below the point where said back is pivoted and adapted to engage the foot rest to elevate the same and to aid in holding the back in approximately a horizontal position, said seat having a flexible front wall provided with a recess at its lower intermediate portion, and a flap secured to the front wall between the ends of the recess and forming leg openings at the opposite ends of the recess.

In testimony whereof, I have affixed my signature.

ARTHUR T. GOODING.
